United States Patent Office.

ANNIE ELLEN TAYLOR, OF PHILADELPHIA, PENNSYLVANIA, ASSIGNOR
TO HARRY TAYLOR, OF SAME PLACE.

Design No. 3,996, dated April 26, 1870.

DESIGN FOR A SHAWL-MANTLE.

The Schedule referred to in these Letters Patent and making part of the same

To all whom it may concern:

Be it known that I, ANNIE ELLEN TAYLOR, of the city of Philadelphia, in the State of Pennsylvania, have invented and produced a new and original Design for a "Metternich;" and I do hereby declare the following to be a specification thereof, reference being had to the annexed drawing, in which—

Figure 1 represents my design as it appears on the wearer, and

Figure 2 represents the same, unfolded.

My design relates to a garment called a "Metternich," of such shape and configuration as to have the appearance of a mantle in front, and of a shawl at the back.

To produce a "Metternich" made according to my design, a narrow strip is cut from one of the long sides of a rectangular piece of goods, to form the collar.

The rectangular piece is then folded double, lengthwise, and cut "bias" near the middle, so as to divide it into three pieces.

The end pieces A and B, which are of the same size

and shape, are sewed together, as shown in the drawing, by seam E F, and the middle piece, which is of triangular shape, is cut lengthwise into halves C and D, which are then doubled lengthwise and sloped at the bottom, so that, when laid with their long edges together, they form an ornament of the shape represented in the drawing.

They are sewed together in this position on the seam E F, forming a pointed ornament, with the point at the neck of the "Metternich."

The collar G H is then sewed on, and the pieces cut from it may be gathered in a fan shape, and used to form trimmings, as shown at I.

Having thus described my invention,

What I claim as new, and desire to secure by Letters Patent of the United States, is—

The design for a "Metternich" or "shawl-mantle," as shown.

ANNIE ELLEN TAYLOR.
